PHOSPHONIUM COMPOUNDS

Wilhelm Lommel and Heinrich Münzel, Leverkusen-Wiesdorf, Germany, assignors, by mesne assignments, to General Aniline & Film Corporation, New York, N. Y., a corporation of Delaware

No Drawing. Application March 30, 1940, Serial No. 327,050. In Germany April 6, 1939

9 Claims. (Cl. 260—389)

This invention relates to a process for the manufacture of new quaternary phosphonium compounds of the following general formula

wherein R₁, R₂, R₃, R₄, R₅, R₆ and R₇ stand for hydrocarbon radicals and R₃ stands for an aryl radical capable of protecting materials against the attack of animal and plant pests and displaying bactericidal and fungicidal properties and to the new quaternary phosphonium compounds obtainable thereby. The radicals standing for R₁—R₈ may be substituted, for instance, by chloro atoms, nitro, alkoxy groups or the like. The terms hydrocarbon radicals, aryl and phenyl radicals used in the specification and in the appended claims are intended to cover the radicals as such as well as the radicals carrying substituents.

Quaternary phosphonium compounds of the above stated general formula have not yet been described in literature and the possibilities for their manufacture appeared to be improbable from the view-point of our present knowledge about quaternary compounds.

Now we have found that phosphonium compounds of this kind can be obtained by adding a halogenmethane compound selected from the group consisting of

wherein R₄, R₅, R₆ and R₇ stand for hydrocarbon radicals and R₃ stands for an aryl radical on a tertiary phosphine. In certain cases the manufacture may be performed by acting with halogenmethane derivatives upon tertiary phosphines in which at least one radical is connected with the phosphorous atom by a secondary or a tertiary carbon atom. The addition is effected suitably by heating if necessary in an acid medium, for instance, in the presence of acetic acid. In

5 this way the halides of the phosphonium compounds are obtained. Other salts may be manufactured by the known methods, for instance, by double decomposition. Thus, for instance, in many cases difficultly soluble salts are formed by adding nitrates or thiocyanates to the aqueous solution of the halides. In many cases the phosphonium compounds obtained may be substituted subsequently, for instance, by chloro atoms or by

10 nitro groups.

15 The new phosphonium compounds represent colorless or weakly colored mostly well crystallizing compounds which mostly dissolve difficultly in cold water but often show a good solubility in hot water. In organic solvents such as ether, acetic ester they are insoluble, easily soluble, however, in alcohol. They display bactericidal and fungicidal properties and protect fabrics such as linen, wool and so on which have been treated with them from being moldered by the attack of fungi. Textile goods liable to the attack of pests such as moths, buffalo moths are protected from damage. The protection attained is far reaching and represents, in many respects, 20 an advance when compared with the protection obtained with the known phosphonium compounds. Thus, for instance, certain members of the new group of the phosphonium compounds show an increased fastness to washing or they 25 surpass the known compounds as regards activity and protect not only against the attack of moths but also of other pests, for instance, anthrenus.

30 The following examples illustrate our invention without, however, restricting it thereto, the parts being by weight.

Example 1

115 parts of triphenylphosphine are heated in an autoclave with 70 parts of phenyl-dimethyl-chloromethane for 12 hours to 150° C. When cool the reaction mass is treated with water and Norit, filtered and the purified solution concentrated in vacuo.

Example 2

390 parts of 4-chlorophenyl-phenyl-chloromethane are heated with 425 parts of triphenylphosphine for 5 hours to 130—140° C., whereby the mass solidifies. When cool the mass is powdered and dissolved in hot water. Little impurities are

filtered off. On cooling the new phosphonium compound crystallizes from the filtrate in white crystals.

Example 3

55 parts of triphenylchloromethane are dissolved in 30 parts of glacial acetic acid. 52 parts of triphenylphosphine are added to the solution and the mixture is heated for 5 hours to 95° C. The glacial acetic acid is distilled in *vacuo* and the residue dissolved in hot water. The triphenyl-triphenylmethyl-phosphonium chloride crystallizes from the filtrate. By treating the reaction product dissolved in glacial acetic acid with chlorine mono-, di-, tri and higher chlorinated derivatives may be obtained, which partly possess a higher solubility in water.

Example 4

32 parts of phenyl-diethylphosphine are heated with the exclusion of air with 53 parts of triphenyl-chloromethane for 4 hours at 150° C. When cool the mass represents a brittle resin. It is dissolved in water, the solution separated from the residue and decolorized with Norit. The aqueous filtrate is evaporated to dryness in *vacuo*.

Example 5

50 parts of triphenylphosphine are heated in an autoclave with 30 parts of tertiary butyl bromide for 8 hours at 145° C. The addition products separates in crystals.

Impregnating the materials to be protected occurs as usual. For instance, the products are dissolved in suitable solvents such as water, alcohol or mixtures and the fabrics are treated therewith at room or higher temperatures.

As further examples of the new class of compounds may be mentioned the addition products of the following halogen-methane derivatives or triphenylphosphine:

3,4-dichlorophenyl-phenyl-chloromethane
Di-(4-chlorophenyl)-chloromethane
Phenyl-naphthyl-bromomethane
4-bromophenyl-phenyl-chloromethane
4-chlorophenyl-diphenyl-chloromethane
4-(N-methylbenzenesulfamido)-phenyl-phenyl-chloromethane
4-(benzenesulfamido)-phenyl-phenyl-chloromethane
9-chlorofluorene
Tolyl-phenyl-chloromethane
2-chlorophenyl-phenyl-chloromethane
4-chlorophenyl-4-methoxyphenyl-chloromethane
2-chlorophenyl-di-(4-chlorophenyl)-chloromethane
4-chlorophenyl-naphthyl-chloromethane
Dimethyl-ethyl-bromomethane
4-nitrophenyl-di-phenyl-chloromethane
4-chlorophenyl-di-phenyl-chloromethane.

Example 6

100 kg. of woolen fabrics are treated in a dye bath 1:30 with 0.1-0.2% of the compounds obtainable according to Example 2 for half an hour at 60° C. Dyestuffs and dyeing agents may be added to the bath. The fabrics, when dried, are protected from the attack of moths.

We claim:

1. As new products the quaternary phosphonium compounds of the following general formula

wherein X stands for a radical selected from the group consisting of

10 R_1-R_7 stands for hydrocarbon radicals and R_8 stands for an aryl radical.

2. As new products the quaternary phosphonium compounds of the following general formula

15 wherein X stands for a radical selected from the group consisting of

20 R_1-R_7 stand for hydrocarbon radicals and R_8 stands for an aryl radical.

3. As new products the quaternary phosphonium compounds of the following general formula

35 wherein X stands for a radical selected from the group consisting of

40 R_1-R_7 stands for hydrocarbon radicals and R_8 stands for an aryl radical.

4. As new products the quaternary phosphonium compounds of the following general formula

50 wherein X stands for a radical selected from the group consisting of

55 R_1-R_8 stand for aryl radicals.

5. As new products the quaternary phosphonium compounds of the following general formula

60 wherein X stands for a radical selected from the group consisting of

65 R_1-R_8 stand for aryl radicals.

6. As new products the quaternary phosphonium compounds of the following general formula

R₁, R₂, R₃ and R₄ stand for phenyl radicals and R₅ stands for a hydrocarbon radical.

7. As a new product the quaternary phosphonium compound of the following formula

5

10

8. As a new product the quaternary phosphonium compound of the following formula

15

20

25

9. As a new product the quaternary phosphonium compound of the following formula

WILHELM LOMMEL,
HEINRICH MÜNZEL.
